LOW TENSION SPARK PLUG

Karl Stuermer, Cleveland, Ohio, assignor to General Motors Corporation, Detroit, Mich., a corporation of Delaware

Application May 10, 1952, Serial No. 287,147

5 Claims. (Cl. 29—25.12)

This invention relates to spark plugs and to a process for making same. More particularly, this invention concerns spark plugs of the type which operate at relatively low voltages and are commonly referred to as low tension or creep gap spark plugs.

One of the objects of this invention is to provide a durable and efficient spark plug which is operative at relatively low voltages and high energies to give an extremely hot spark. Another object of the invention is to provide a low tension spark plug of the type wherein the spark path abutting surface of the insulator has increased wear resistance, thus greatly increasing the efficiency and operating life of the plug. Still another object of the invention is the provision of a novel process for making low tension spark plugs of increased efficiency and durability.

These objects are carried out in accordance with the invention by providing a spark plug having a surface portion of the insulator abutting the spark gap and then treating the spark gap abutting surface portion of the insulator in the manner hereinafter described to condition the plug for low tension operation.

Other objects and advantages of my invention will be apparent in the following description and from the accompanying drawings in which Figure 1 is a schematic showing of apparatus which may be used for the practice of the process of this invention. Figure 2 is a side view in section of one embodiment of a low tension spark plug of this invention. Figure 3 is an enlarged sectional view of a bottom portion of the spark plug shown in Figure 2 after the first step of the process of this invention is completed, and Figure 4 is a bottom view taken on the line 4—4 of Figure 3.

Referring now to the drawing, Figure 1 shows a spark plug 4, an electrical circuit 5 for applying a voltage to the spark plug and including an electrical power source as indicated.

The construction of the particular spark plug 4 in Figure 1 is shown in detail by Figure 2. In order to more clearly describe and explain the invention, the structure of the spark plug prior to the conditioning process will now be described.

Referring to Figure 2, the spark plug includes an outer shell 6, an insulator 8, and a centerwire 10 positioned in the longitudinally extending centerbore 12 of the insulator 8.

The centerwire 10 comprises a centerwire screw 14, an electrical conducting seal 16 and a central electrode spindle 18. The centerwire screw 14 is provided with an electrical contact head 20 for connection with the ignition wiring system and a threaded portion 22 which is embedded in the electrical conducting seal 16 to retain the centerwire screw within the bore 12. The conductive seal 16 which may consist of a mixture of glass and some conductive material such as copper or nickel powder is bonded to the walls of the insulator centerbore 12, thus providing a gas-tight seal and is also bonded to the

2

top of the central electrode spindle 18 and to the centerwire screw to secure these parts in position.

The bottom of the central electrode spindle 18 extends to the exterior of the centerbore and is provided with a head 24 while the top is bifurcated to provide a pair of prongs 26 which are bent outwardly and over the top of a metal electrode retainer ring 28 to secure the central electrode in the lower end of the insulator centerbore 12. It will be noted that the lower end of the centerbore is of reduced diameter, thus providing a centerbore shoulder 30 to support the retainer ring 28.

In the particular embodiment shown in Figure 2, the insulator 8 is of one-piece construction and is provided with an outwardly extending annular shoulder 34 and a cylindrical base portion 36 which terminates in a flat surface 38. The surface 38 is conditioned to provide low tension spark plug operation by the process hereinafter described. It is this spark gap abutting insulator surface 38 to which this invention chiefly relates.

The outer metal shell 6 has a threaded portion 40 of reduced diameter for engagement with a threaded hole provided in the cylinder head of an internal combustion engine.

The outer or ground electrode consists of an inwardly extending annular flange 42 which is secured to the metal shell 6 and which, in the embodiment shown, is integral with the ground shell. The edge of the ground electrode is in continuous spaced relation to the edge of the central electrode head, thus providing a circular spark gap 44.

Besides serving as the ground electrode, the flange 42 also cooperates with a circumferential inwardly turned lip 46 on the top of the shell 6 to retain the insulator in position. A metal washer 48 between the insulator shoulder 34 and the lip 46 serves to seal the structure and also to assure a secure fit.

Interposed between the head 24 of the central electrode spindle 18 and the flat base surface 38 of the insulator 8 is an annular gasket 50 of some suitable heat and wear-resistant metal such as nickel or a nickel alloy. A second annular gasket 52 also of a heat and wear-resistant metal such as nickel or a nickel alloy is interposed between the flange 42, which serves as the outer electrode, and the base surface 38 of the insulator.

The gaskets 50 and 52 are pressed tightly into continuous mechanical and electrical contact with the abutting surfaces of the electrodes and of the insulator and thus serve not only to inhibit gap erosion and electrode undermining but also as a gas-tight seal for the assembly.

The insulator 8, or at least that portion of the insulator adjacent the spark gap, should preferably have a particularly high heat resistance to withstand the high discharge temperatures. I prefer to use a sintered alumina type insulator material principally because of its high mechanical strength, high heat resistance and high fusing temperature.

It is to be understood that the specific structure of the spark plug shown and described herein is given merely for purposes of illustration and that numerous other embodiments are possible and are within the full and intended scope of the invention. The only essential characteristic of the spark plug structure is that it is provided with an insulator having a surface portion positioned between the electrode firing tips and adjacent the spark gap so as to provide an insulator surface abutting path for the electrical discharges during operation of the plug.

As thus far described, the spark plug is not adapted for use in a low tension ignition system. It is the conditioning process now to be described which adapts the plug for low tension operation.

As the first step in the conditioning process, the spark gap abutting the surface 38 of the insulator is provided with a transitory film or coating 54 of some suitable conductive material. This is shown in Figures 3 and 4. The transitory coating 54 may be graphite or carbon black or any other material which has similar electrical properties and which will be rapidly destroyed or removed by electrical discharges across the spark gap.

Any suitable means may be used to provide the coating 54. If carbon black or graphite is used, it can be 10 brushed or smeared on to the insulator surface. Alternatively, the coating or film can be put on in the form of an emulsion such as Aquadag (a water suspension of colloidal graphite) and the liquid medium subsequently evaporated. I have found it preferable to use this latter method since a more uniform coating can thereby be attained.

By the term "transitory coating" as used herein is meant a coating such as will be destroyed or removed from the insulator surface during the subsequent conditioning steps to be hereinafter described. By the term "conductive" I intend also to include those materials which are often referred to as semi-conductive.

Referring again to Figure 1, the spark plug 4, after the coating 54 has been applied, is placed into an electrical circuit 5 as schematically shown and an electrical discharge or a series of electrical discharges is applied across the spark gap. The amount of voltage necessary to initially cause a discharge across the spark gap will of course vary with the size of the spark gap along with the nature of the transitory coating 54. When graphite is used as the coating material the initial voltage necessary to cause discharge in the conditioning treatment will generally be somewhat less than the operating voltage for which the spark plug is designed after the conditioning treatment. Thus, for example, if the spark plug is designed for use at 2000 volts after conditioning, the initial voltage used in the conditioning treatment may be about 1500 volts.

During the application of the electrical discharge across the spark gap, the transitory coating 54 is worn or burned off the surface of the insulator; however, by the time the destruction of the coating is completed, the spark plug will have been conditioned to operate at low voltage with the hard and wear-resistant lower portion of the insulator intact.

The length of the conditioning treatment depends of course on the type of spark plug, on the amount of voltage used, and on the precise conditions under which the voltage is applied. For example, a short surge of an extremely high voltage might be used, or a somewhat longer surge of a lower voltage. Thus, the time can be anywhere from a fraction of a second up to a number of minutes.

It is preferable to use a series of electrical discharges for the conditioning treatment rather than one continuous discharge. I prefer to use repeated condenser discharges as the power source; however, either a capacitive or an inductive discharge system may of course be used. Polarity is not significant in the process; either the positive or negative pole may be connected to the center electrode.

It is often preferable during at least a portion of the conditioning process to submerge the firing end of the spark plug in a liquid electrical insulating medium such as kerosene or other light insulating oil during the application of the electrical discharges. The insulating oil serves the purpose of confining the discharge within the spark gap and this has been found to enhance the conditioning treatment. Ordinarily, during operation in air, the discharge tends to bulge out of the gap due to magnetic and thermal effects. This is of course quite desirable during operation of the plug as an internal combustion engine igniter; however, during the conditioning treatment, it is preferable to confine the spark within the

gap and this is what is accomplished by the use of the liquid electrical insulating medium as above described.

The following example of a typical conditioning process will serve to better illustrate the invention:

Step 1.—Apply a coating of graphite to the spark gap abutting surface of the insulator by the application of Aquadag and subsequent evaporation of the water from the spark gap.

Step 2.—Spark the plug by the discharge of a condenser of approximately 2 mfd. charged to a voltage of the order of 1500 volts at a rate of 10 to 30 sparks per second for about 30 seconds. Approximately 2 joules.

Step 3.—Spark the plug under oil (insulating oil or kerosene) by discharge of a condenser of approximately 2 mfd. charged to a voltage of the order of 1500 volts at a rate of 10 to 30 sparks per second for about one minute. Approximately 2 joules.

Step 4.—Spark the plug in air under identical conditions as in Step 3 for about one minute or until the minimum sparking voltage of the plug is 500 volts or lower.

When the conditioning treatment is complete the original film of conductive material will have been destroyed, the plug nevertheless continuing to operate as a low tension igniter. The spark plug conditioned by the above outlined process was of the type shown in Figure 1 and had a gap size of .01 inch. After treatment, it operated efficiently as a creepage gap plug in a 2000 volt circuit and had an extremely long life.

It is to be understood that the above example is given 30 merely for purposes of illustration and that other modifications can be used within the full and intended scope of the invention.

Exactly what occurs to the plug during the application 35 of the voltage to destroy the transitory conductive film and at the same time to render the plug adaptable for use in low tension systems is not fully known. It is believed that minute amounts of the electrode materials, or of the transitory film, or of the insulating oil decomposition products, or some combination of these, are spattered onto the surface of the insulator shown at 38 in Figure 2 to render it semi-conductive. Whatever the precise nature of the spark plug or of the insulator surface might be after the treatment is completed, it has been found that the thus conditioned plugs not only operate very efficiently in a low tension system but also have a greatly increased operating life over other and prior types of creepage gap plugs.

One reason for the longer life of the spark plugs of this invention is that, in order to obtain creepage gap operation, no layer on the face of the insulator of the type used in prior low tension igniters is used. Because of this, the material for the spark gap abutting face of the insulator can be chosen solely for its properties of heat and wear resistance and mechanical strength. Thus, that part of the igniter most subject to wear and stress can be specifically designed to meet the high demand for strength and durability, and then by means of the novel process of this invention creep gap properties may be imparted.

Various changes and modifications of the embodiments 60 of the invention described herein may be made by those skilled in the art without departing from the spirit and principles of the invention.

I claim:

1. A process for treating a spark plug of the type comprising a pair of electrodes having end portions in spaced relationship to form a spark gap therebetween and an electrical insulator separating said electrodes and having a surface portion interposed between said electrode end portions and adjacent said spark gap, said process comprising the steps of providing said surface portion with a carbon coating, applying an electrical discharge across said spark gap while in air, submerging said spark gap in a liquid electrical insulating medium and applying an electrical discharge across said spark gap while sub-

merged to condition said spark plug for operation in a low voltage system.

2. A process for making a low tension spark plug of the type having a pair of electrodes with end portions in spaced relationship to form a spark gap therebetween, comprising the steps of positioning a surface having good electrical insulating properties between said electrode end portions and adjacent said spark gap, providing said surface with a graphite coating, applying a series of electrical discharges across said gap while in air, submerging said spark gap in a liquid electrical insulating medium and applying a series of electrical discharges across said gap while submerged and then removing said spark gap from said medium and applying a series of electrical discharges across said spark gap while in air.

3. A process for making a low tension spark plug of the type having a pair of electrodes with end portions in spaced relationship to form a spark gap therebetween, comprising the steps of positioning a surface having good electrical insulating properties between said electrode end portions and adjacent said spark gap, applying a suspension of graphite to said surface and evaporating the liquid from said suspension to provide a film of graphite on said surface, applying a series of electrical discharges of about 1500 volts across said spark gap for about thirty seconds while in air, submerging said spark gap in an electrical insulating oil and applying a series of discharges of about 1500 volts across said spark gap for about one minute while submerged and then removing said spark gap from said medium and applying a series of discharges of about 1500 volts across said spark gap while in air.

4. A process for treating a spark plug of the type

comprising a pair of electrodes having end portions in spaced relationship to form a spark gap therebetween and an electrical insulator separating said electrodes and having a surface portion interposed between said electrode end portions and adjacent said spark gap, said process comprising the steps of providing a transitory conductive coating on said surface portion, submerging the spark gap of said spark plug in a liquid electrical insulating medium and applying an electrical discharge across said spark gap while submerged to condition said spark plug for operation in a low voltage system.

5. A process for treating a spark plug of the type comprising a pair of electrodes having end portions in spaced relationship to form a spark gap therebetween and an electrical insulator separating said electrodes and having

15 a surface portion interposed between said electrode end portions and adjacent said spark gap, said process comprising the steps of providing a transitory conductive coating on said surface portion, submerging the spark gap of said spark plug in a liquid electrical insulating medium and applying a series of electrical discharges across said spark gap while submerged to condition said spark plug for operation in a low voltage system.
